UNITED STATES PATENT OFFICE.

CARL H. BISSELL, OF SYRACUSE, NEW YORK, ASSIGNOR TO CROUSE-HINDS COMPANY,
OF SYRACUSE, NEW YORK, A CORPORATION OF NEW YORK.

ELECTRIC SWITCH.

Application filed April 4, 1917. Serial No. 159,763.

To all whom it may concern:

Be it known that I, CARL H. BISSELL, a citizen of the United States, and a resident of Syracuse, in the county of Onondaga and 5 State of New York, have invented a certain new and useful Electric Switch, of which the following is a specification.

This invention relates to electric switches, and has for its object a particularly simple 10 and efficient mechanism by which a quick make-and-break action of the switch is effected, which mechanism is particularly simple and compact in construction, and highly efficient and durable in use; and the 15 invention consists in the combinations and constructions hereinafter set forth and claimed.

In describing this invention, reference is had to the accompanying drawings, in 20 which like characters designate corresponding parts in all the views.

Figure 1 is a side elevation of a switch embodying my invention, the contiguous portion of a panel board base and the facing 25 of a panel board being also shown.

Figure 2 is a plan view, partly broken away and partly in section, of parts seen in Fig. 1, the cover of the panel board being omitted.

Figure 3 is an end elevation of parts seen in Fig. 1.

Figure 4 is a sectional view taken on line 4—4, Fig. 3.

This switch comprises, generally, a switch member, an operating member, and means for transmitting the movement of the operating member to the switch member to effect a quick make-and-break action. Said members preferably move in opposite directions 40 with respect to each other; and said means includes a spring shiftable by the operating member to tension the spring and to change the direction of the force of the spring on the switch member, so that the spring acts 45 on the switch member first in one direction and then in the opposite direction.

The switch also includes means by which the shifting movement of the spring to change the direction of its force, is accelerated or increased in order to facilitate the 50 quick acting feature of the switch. I have here illustrated the switch as embodied in a panel board construction.

1 designates the panel board base; 2, the cover or facing of the panel board. 3 are 55 fuse plug sockets in which fuse plugs 4 are located.

5 designates the base of the switch, which base is mounted on the panel board base 1; and 6, 6' and 7, 7', are pairs of switch contacts mounted on the base and connected respectively to pairs of conductor bars 8, 8' and 9, 9', by means of screws 10, 10' and 11, 11', the bars 8, 8', 9, 9' being mounted on the base of the panel board and connected 60 in the electric system of the panel board.

12 designates the switch member which includes a bar of insulation and pairs of knives or conductors 13, 14 coupled or carried by the bar and movable into and out 70 of contact respectively with the terminals 6, 6' and 7, 7'. 15 designates the operating member which projects through the facing or cover 2. One of these members 12, 15 and preferably both are movable about 75 axes, back and forth and in reverse directions with respect to each other, that is, while one member moves clockwise the other moves anti-clockwise and vice versa.

The spring forming part of the means for 80 transmitting the motion of the operating member to the switch member is normally arranged upon one side or the other of the axes of said members and is shiftable to the other side of said axes, in order that 85 the direction of the force of the spring on the switch member may be reversed. The force of the spring is applied in one direction on one side of said axes, and during the movement of the operating member in one 90 direction, the spring is shifted to the other side of the axes; and during the movement of the operating member in the reversed direction, the force is applied in the opposite direction on the switch member. The 95 switch member 12 is here shown as pivoted at 16 to the free ends of the brackets 17 rising from the base 5, the pivots passing through extensions of the knives 13, 14 and being located at points remote from and between the contact ends of the knives. That is, the contact ends are located in different 100 radii from the axis 16.

The operating member 15, as here illustrated, includes arms 18 pivoted at 19 to the 105 brackets 17 near the switch base 5, and a

cap portion of insulation mounted on the arms 18 and being of such shape as to always close the slot 20 in the cover 2 of the panel board in any position of the operating member. A suitable handle portion 21 is mounted on the cap 15.

22 is the spring forming part of the mechanism for transmitting the motion of the operating member 15 to the switch member 12, the spring being connected at its opposite ends respectively, to said members. It is connected to one of said members 12, 15 by a movable part shiftable in the direction of movement of said member, in order to facilitate the shifting of the spring from either side to the other of the axes 16, 19, and to quickly tension said spring and change its position relatively to the switch member 12, and hence change the direction 20 in which the force is applied to said switch member 12.

In this embodiment of my invention, the spring 22 is a tension spring connected at one end to a bracket 23 mounted on the insulating bar of the switch 12 midway between the knives 13, 14, and at its other end to a coupling 22^a, which engages the eccentric or crank portion 24 of a rocking part or shaft 25 journaled in the arms 18 of the operating member at a point remote from the axis 19 of said arms. The point of connection of the spring 22 of the switch member 12 or the bracket 23 thereof, moves in the space between the switch contacts 7, 7', and 8, 8'.

35 The rocking part or shaft 25 moves in the direction of the operating member 15 and in a direction contrary to the movement of the switch member 12, and the rocking of the shaft 25 is effected by any suitable means 40 as an arm 27 rigidly mounted on the rock shaft 25 and extending in the opposite direction from that of the crank portion 24, the arm 27 having a lengthwise slot 28 therein through which a pin extends which pin is 45 carried by the bracket arm 17. Said pin is usually an extension of the pivot 16. There is usually an arm 27 at each end of the shaft 25, and the extensions of the pivots 16 usually extend into arc-shaped slots 29 in the 50 arms 18 of the operating member.

The throw of the switch member is limited by stop shoulders 30 projecting from the brackets 17 into slots 31 formed respectively in the switch blades 13, 14.

55 In operation, assume that the switch is off, that is, the parts are in their position shown in Fig. 4. Upon the moving of the operating member 15 to the left or anti-clockwise into the position shown in Fig. 1, the spring 22 60 is first tensioned due to the rocking movement of the shaft 25, and after the crank portion 24 of the shaft passes to the left hand side of the axis 16, the pull of the spring under tension is then applied to the 65 left on the switch member 12 and the switch

member caused to move in a clockwise direction on its pivot, engaging the knives with the contacts 7, 7', 8, 8'.

Movement of the operating member clockwise from its position shown in Fig. 1 rocks 70 the shaft 25 in the same direction first tensioning the spring 22 and shifting the spring to the right hand side of the axis 16, when the force of the spring 23 quickly moves the switch anti-clockwise bringing the 75 knives 13, 14 out of engagement with the contacts 7, 7', and 8, 8'.

During the movement of the operating member 15, the arms 27 fulcrum on the pivots 16 for the switch member, and owing to the 80 slots 28 therein are permitted to move endwise or radially relatively to the pivots 16 as the angle of said arms change. When the crank 24 has moved far enough so that the line of pull of the spring 22 moves from one side as the right side in Fig. 4 of the axis of the pivot 16 to the left side thereof, the spring moves the switch 14 anti-clockwise or to the left, Fig. 4.

The arms 27 likewise fulcrum on the 90 pivots 16 in the same manner during the movement of the operating member 15 in a clockwise direction from its position shown in Fig. 1 to that shown in Fig. 4.

What I claim is:

1. A switch comprising a movable switch member, and an operating member movable in reverse directions with respect to each other, and one of said members being movable about an axis, means for transmitting 100 and reversing the motion of the operating member to the switch member comprising a spring extending in a direction crosswise of said axis, a rocking part carried by one of said members and movable from either side to the other of said axis in the direction of movement of the member to which it is connected, the spring being connected at one end to said part, and means for rocking said part during the movement of the operating 105 member, substantially as and for the purpose specified.

2. A switch comprising a switch member and an operating member pivoted on parallel axes spaced apart, a spring connected at 110 one end to the switch member and extending crosswise of said axes, a rocking part carried by the operating member at a point remote from its axis and normally arranged on the same side of the axis of the switch member on which the spring is located, and movable relatively to the operating member in the same direction as the operating member to the other side of said axis and means for rocking said part, substantially 115 as and for the purpose set forth.

3. A switch comprising a base, brackets mounted on the base, a switch member pivoted to the support, a switch member pivoted to the brackets near the free ends 120

- thereof and movable between the brackets, an operating member having arms pivoted to the brackets near the base, and means for transmitting the motion of the operating member to the switch member, substantially as and for the purpose described.
4. A switch comprising a base, brackets mounted on the base, a switch member pivoted to the support, a switch member pivoted to the brackets near the free ends thereof and movable between the brackets, an operating member having arms pivoted to the brackets near the base, and means for transmitting the motion of the operating member to the switch member, including a spring connected at one end to the switch member below the pivot thereof and at its other end to the operating member above the pivot of the switch member, substantially as and for the purpose specified.
5. A switch comprising a base, brackets mounted on the base, a switch member pivoted to the brackets near the free ends thereof and movable between the brackets, an operating member having arms pivoted to the brackets near the base, and means for transmitting the motion of the operating member to the switch member, including a rock shaft carried by the operating member above the pivot of the switch member and having a crank portion and an arm extending in opposite directions from the shaft, the last mentioned arm being formed with a slot, a pin fixed from movement extending into the said slot, and a spring connected at one end to the crank portion of the rock shaft and at its other end to the switch member, substantially as and for the purpose set forth.
6. A switch comprising a base, a support mounted on the base, an operating member pivoted to the support at a point between the base and the pivot of the switch member, and means for transmitting the motion of the operating member to the switch member, said means including a rock shaft carried by the operating member above the pivot of the switch member and having a crank portion and an arm extending in different directions from the shaft, the arm being formed with a slot, a fulcrum pin on the support and extending into the slot and a spring connected at one end to the crank portion of the rock
- arm and at its other end to the switch member, substantially as and for the purpose set forth.
7. A switch comprising a support, a switch member pivoted to the support, an operating member pivoted to the support and means for transmitting motion of the operating member to the switch member including a rock shaft carried by the operating member and having a crank portion and a spring connected at one end to the crank portion of the rock shaft and at its other end to the switch member, the spring and rock shaft being normally arranged on one side of the axes of said members and the rock shaft being shiftable to the opposite side of said axes, whereby the switch member is given a snap action and the rock shaft moved about its axis and means for normally holding the rock shaft from movement about its axis until the rock shaft has passed to the opposite side of the axis of the switch member, substantially as and for the purpose set forth.
8. A switch comprising a support, a switch member pivoted to the support, an operating member pivoted to the support and means for transmitting the motion of the operating member to the switch member including a rock shaft carried by the operating member and having a crank portion and a spring connected at one end to the crank portion of the rock shaft and at its other end to the switch member, the spring and rock shaft being normally arranged on one side of the axes of said members and the rock shaft being shiftable to the opposite side of said axis, whereby the switch member is given a snap action and the rock shaft moved about its axis, the operating member being formed with a slot extending transversely of the axis of the switch member and below the same and the rock shaft having an arm rigid therewith and formed with a pin movable in the slot, the opposite ends of the slot forming stops for limiting the movement of the rock shaft, substantially as and for the purpose described.
- In testimony whereof, I have hereunto signed my name, at Syracuse, in the county of Onondaga, and State of New York, this 27th day of October, 1916.
- CARL H. BISSELL.

Certificate of Correction.

It is hereby certified that in Letters Patent No. 1,430,718, granted October 3, 1922, upon the application of Carl H. Bissell, of Syracuse, New York, for an improvement in "Electric Switches," errors appear in the printed specification requiring correction as follows: Page 2, lines 128 and 129, claim 3, and page 3, lines 8 and 9, claim 4, strike out the words "a switch member pivoted to the support"; same page, line 41, claim 6, after the word "base" insert the words *a switch member pivoted to the support*; and that the said Letters Patent should be read with these corrections therein that the same may conform to the record of the case in the Patent Office.

Signed and sealed this 12th day of December, A. D., 1922.

[SEAL.]

KARL FENNING,
Acting Commissioner of Patents.
